UNITED STATES PATENT OFFICE

DANIEL F. SHELDON, OF MONTALVO, CALIFORNIA

SKELETON TETRAHEDRON FOR JETTIES AND CURRENT DEFLECTORS

Application filed October 31, 1928. Serial No. 316,125.

This invention relates to improvements in devices of the character set forth in Patent No. 1,140,140, granted to myself and another, May 18, 1915.

Under said patent, tetrahedron skeletons are provided for location in the bed of a stream for the purpose of causing sand and silt carried by the stream to deposit where required for building up or protecting the banks and for straightening the course of the stream.

Skeleton tetrahedrons for use for the purpose set forth must be massive and strong and are made of a metallic framework on which concrete is molded to form the corners and beams or legs.

There are various objections to building such structures at the places where they are to be used, as the manufacture thereof can only be economically carried on by the use of heavy machinery; and more satisfactory work may be performed at a central plant or station where machinery for mixing and pouring the concrete is provided, and the materials necessary for making the structure can be assembled conveniently; but owing to the great weight and unwieldy character of the individual units, it is very difficult to transport the structures from a central place of manufacture and locate them at the places of use.

An object of this invention is to provide a practical skeleton tetrahedron adapted for manufacture in separate parts that may be transported independently of each other to the place of use, and to make provision whereby such parts may be readily assembled and fastened together in set up form at the place of use, and there made into integral units.

Another object is to produce a stronger skeleton tetrahedron than heretofore; and in carrying out the invention I have provided reinforced concrete individual parts comprising apex members and leg sections, each part having seats complementary to seats on another part and adapted to be juxtaposed when the parts are assembled; and from which juxtaposed parts, the reinforcements project in complementary arrangements; and I provide means whereby juxtaposed reinforce

projections of one face may be secured to the reinforce projections of another face, so that the apices and the leg sections may be separately moved from the place of manufacture to the place of use and there be set up and fitted to each other and secured together, and finally completed by filling with concrete the open spaces surrounding the connected reinforcements at the joints.

Another object of the invention is to secure maximum strength in a composite reinforced concrete skeleton tetrahedron and particularly to strengthen the corner pieces, and dispose the parts to maximum advantage of anchoring efficiency.

Features of the invention are also found in the forms and arrangements of the reinforcing rods and the eyes thereof, whereby the strength of the corner pieces is secured and, whereby it is made possible to connect the corner piece stubs with the leg sections and thoroughly protect the metal connections at the joints.

An advantage arising from this invention is superior anchoring weight and strength at the corners.

Other objects, advantages and features of invention may appear from the accompanying drawings, the subjoined detailed description and the appended claims.

The accompanying drawings illustrate the invention.

Figure 1 is a plan view of a skeleton tetrahedron forming a jetty unit constructed in accordance with this invention.

Fig. 2 is a side view of the same.

Fig. 3 is a front view.

Fig. 4 is an enlarged fragmental diagrammatic view of one of the leg sections.

Fig. 5 is an end view of the leg section shown in Fig. 4.

Fig. 6 is a detail view of a set of the thirteen rods for each of the four corner pieces; the bent rods are shown as stood up, and viewed in perspective; and one of the nine tie bands for the three stubs of each corner piece. It is understood that the two legs of each bent rod are of the same length; the left legs in the view being foreshortened by the nature of the perspective.

Fig. 7 is a perspective view of a nest of the rods and the bands of a corner piece, all in the proper arrangement for cement pouring, the form for molding the cement not being shown, and the outline of the cement body and stubs of the corner piece being indicated by broken lines.

Fig. 8 is an enlarged detail view looking at the apex of one of the corner pieces, with stubs ready for connection with legs; the upper reinforcing rods being indicated in broken lines.

Figs. 9, 10 and 11 are end views respectively, of the three stubs shown in Fig. 8, showing the arrangement of the connecting eyes.

Fig. 12 is a side view of a corner piece detached, the disposition and arrangement of some of the reinforcing rods being shown in broken lines.

Fig. 13 is a fragmental view showing an assembly at an unfinished joint between a leg member and one of its stubs.

Fig. 14 is a detail viewed at right angles to Fig. 13.

Fig. 15 is an elevation of a corner piece in section in a plane central to one of the stubs on line $\alpha 15$, Figs. 8 and 11.

The skeleton tetrahedron is composed of four corner pieces or members 1, all of which are alike, six leg sections 2, which are alike, and twelve joints 3, which are alike, connecting the leg sections to the stubs of the corner leg pieces.

Each corner member, or apex comprises a junction body 4, a cap 5 and three divergent stubs 6, 7, 8, flaring from a common apex or source and is composed of concrete with steel rod reinforcement. Each corner piece is reinforced by a nest assembly of tri-loop bent reinforcing rods $b, a'', a', a, d, e, c'', c', c, b'', b'$, criss-crossing each other at their intermediate loops within the junction body 4, (Fig. 7) forming a nest or frame formation inside the corner piece, and having terminal bends forming open eyes $9b, 9a'', 9a', 9a, 9d, 9e, 9c'', 9c', 9c, 9b'', 9b'$, projecting beyond the end faces 10 of the stubs free of the stubs, and relatively arranged for alignment to receive connecting pins 11, (Fig. 13) for holding the stubs and leg sections together in axial alignment.

From Fig. 7, it will be apparent, that the reinforcing rods $b, a'', a', a, \dots$, comprise the rigid framework which is used as a mount for the cement poured over and through the network or nest formed by the reinforcing rods. The reinforcing rod a of the stub member 9 extends longitudinally of such member and across the corner section 5 and extends through the length of the stub member 8, terminating in the loop $9a$. In like manner the remaining rods disposed within the stub member 9, with the exception of the reinforcing rods f and g , extend the length

of the stub 9 and project longitudinally of the stub member 8.

Similarly, the reinforcing rods c'', c', b'', b' , extend the length of the stub 7 and across the corner 5 and project across the length of stub 8. As previously indicated, each of said rods terminate in loops extending below the surface 10. Tie wires h are preferably positioned along the frame work of the reinforcement rods to hold the latter in proper adjustment.

The leg sections 2 are provided with reinforcing rods having straight bodies 12 and terminal eyes or looped portions 13, that project from the plain faces 14 of the ends of the leg members. The eyes at the ends of the stubs and leg sections are alike and are adapted and arranged to be juxtaposed to receive the pins 11 which are preferably in the form of bolts having nuts 15 to hold the pairs of juxtaposed eyes together. There are eight parallel reinforcing rods (Fig. 5) in each leg; and said rods extend from end to end of the leg section and terminate at their opposite ends in the projecting eyes 13.

Each corner piece is provided with thirteen reinforcing rods $e, d, a, a', a'', b, f, g, c'', c', c, b'', b'$, and nine ties h .

There are seven forms of reinforcing rods in each corner piece, and the ties are formed of wires or rods bent around the parallel portions of the reinforcing rods in the stubs after the usual manner of banding parallel reinforcing rods in reinforced concrete structures preparatory to pouring the concrete.

The eyes are in the form of loops which are economically made by bending the rod terminals to form a U bend, the base of which will protrude beyond the end of the stub or the leg section a distance a little more than half the width of the gap required between the ends of the stub and leg at each joint defining the gap, to allow the constructor to insert the pins 11 through the loops and make them secure before filling the gap with concrete or other cementitious material to complete the reinforced joint.

The body of the rod beyond the base of the loop is of sufficient length to be embedded in the body of the leg or stub as the case may be when the same is molded at the place of manufacture.

From the foregoing description considered in connection with the accompanying drawings, it is believed that the several novel structural features of my present improvement, as well as the advantages thereof in practical operation, will be readily appreciated.

Because of the simple form of the various elements entering into the described construction, the device may be produced at comparatively small manufacturing cost.

I have described and illustrated in the accompanying drawings a structural embodied

ment of the device which I have found to give highly satisfactory results, and it will be obvious to those skilled in the art, after an understanding of my invention, that other changes and modifications may be made without departing from the spirit and scope of my invention and I aim in the appended claims to cover such modifications as are within the scope of my invention.

10 I claim:—

10 1. A corner member for a skeleton tetrahedron comprising divergent stubs flaring from a common source, each stub being provided with reinforced rods co-extensive the 15 length thereof and terminating in spaced loops.

20 2. A corner member comprising divergent stubs flaring from a common source, reinforcing rods extending longitudinally of a pair of contiguous stubs and across the corner member, and loops extending from said rods free of the stubs.

25 3. A corner member comprising contiguous divergent stubs, reinforcing rods connecting a pair of said stubs, loops projecting from said rods free of said stubs, said rods comprising a nest frame formation under said corner.

30 In testimony whereof, I have hereunto set my hand at Ventura, California, this 22 day of October, 1928.

DANIEL F. SHELDON.
